CLAIM

The ornamental design for a “scoop,” as shown and described.

DESCRIPTION

FIG. 1 is a top, rear, and right side perspective view showing a transparent embodiment of our new design for a scoop;

FIG. 2 is a right side view of the scoop shown in FIG. 1, the left side view being a minor image thereof;

FIG. 3 is a rear view of the scoop shown in FIG. 1;

FIG. 4 is a front view of the scoop shown in FIG. 1;

FIG. 5 is a top view of the scoop shown in FIG. 1;

FIG. 6 is a bottom view of the scoop shown in FIG. 1;

FIG. 7 is a top, rear, and right side perspective view showing an alternate opaque embodiment of our new design for a scoop;

FIG. 8 is a right side view of the scoop shown in FIG. 7, the left side view being a minor image thereof;

FIG. 9 is a rear view of the scoop shown in FIG. 7;

FIG. 10 is a front view of the scoop shown in FIG. 7;

FIG. 11 is a top view of the scoop shown in FIG. 7; and,

FIG. 12 is a bottom view of the scoop shown in FIG. 7.
